CLAIM

The ornamental design for a combined beverage insulator sleeve and smoking article holder substantially as shown and described.

DESCRIPTION

FIG. 1 is a perspective view of a combined beverage insulator sleeve and smoking article holder shown in use; FIG. 2 is a front quarter turn thereof of the flexible smoking article holder;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines are for illustrative purpose only and form no part of the claim design.
